UNITED STATES PATENT OFFICE

MICHAEL J. MCRAE, OF SCRANTON, PENNSYLVANIA

FLYER CONSTRUCTION

Application filed May 31, 1930. Serial No. 458,212.

This invention relates to improvements in flyer devices and more particularly to a novel flyer cap adapted to permit the use of readily replaceable flyer wires.

Hitherto, it has been proposed to use wooden and brass flyer blocks for the mounting of the customary flyer wires. In the use of these constructions, it has been necessary to thread the wires in and upon the wooden blocks and then form the arms and eyelets after such threading operation. When the flyer wires wear out, as they usually do after two or three weeks operation, it is necessary, either to throw away the flyer block or to remove it from the machine and rewire it. This latter, as indicated above, is an expensive and time-consuming job and does not permit of any savings in operating time, it being necessary to keep a duplicate set of blocks in order to prevent shutting down of spindles when breakage of the wires occurs.

It is an object of the present invention to provide a novel flyer cap adapted to operate with wooden and brass flyer blocks.

It is another object of this invention to provide such an improved cap which is so constituted and arranged as to permit the use of readily replaceable flyer wires with wooden and brass flyer blocks, of the above described type.

Another object of this invention is the provision of the improved wooden flyer block having a novel flyer cap adapted to retain replaceable flyer wires in position without the use of a mill nut.

These and other desirable objects and advantages of the present invention will be described in the accompanying specification and illustrated in the drawings, certain preferred embodiments being shown by way of illustration only, for, since the underlying principles may be embodied in other specific mechanical devices, without departing from the spirit and scope of the present invention, it is not intended to be limited to the forms here shown except as such limitations are clearly imposed by the appended claims.

In the drawings like numerals refer to similar parts throughout the several views of which

Fig. 1 is a vertical section of a flyer block having an offset portion adapted to engage a bobbin bushing and being provided with a novel flyer cap;

Fig. 2 is a view similar to Fig. 1, showing a wooden flyer block mounted on a spindle and having its associated flyer wires held in position by a flyer cap;

Fig. 3 is an elevation of a novel flyer cap showing means for retaining a plurality of flyer wires.

Fig. 4 is a view similar to Fig. 3 showing means for retaining a single flyer wire;

Referring now to the drawings, there is shown in Fig. 1 the usual bobbin 1 mounted on a spindle 2. The latter is uniform in diameter and its upper portion is adapted to receive a flyer block 3 having an offset lower portion 4 adapted to engage flange 5 of the bushing inserted in the bobbin. At its upper end the member 3 is provided with a hub portion 6 having a central groove 7 and a bearing surface 7a adapted to receive the usual hump or central half round portion of a flyer wire 8 having the usual eyelet 9 and depending arm 10. A flyer cap 11 having a plurality of apertures 12 and 13 oppositely disposed with respect to each other at the one edge thereof, and a central aperture 14 adapted for engagement with the hub 15 of member 3 is slipped over the flyer block. In operation, the flyer block is inserted in the bushing 5 of the bobbin 1 and the assembly is then placed over and on the spindle 2, the offset portion 4 of the block being thus forced integrally into engagement with the underside of the member 5.

A flyer wire 8 having a central portion adapted to engage channel 7 and abutting against section 7a as a bearing surface is inserted in position, the flyer cap is next lowered into position over the hub 15 of the block. The arms 8 of the flyer wire are bent away from the central portion thereof which is in abutment against the block, until the said arms engage the slots 12 and/or 13 of the said caps being held in position thereby and serving to tense the flyer wires in place.

In the modification shown in Fig. 2, the usual bobbin 1 is mounted on a spindle 20

of tapering cross section adapted to engage a wooden flyer block 21. This latter is provided with the usual groove 22 for receiving the flyer wire 23. The flyer wire has depending arms 24 and thread engaging eyelets 25 as well as the usual central portion engaging the slot 22 in the flyer block. A flyer cap 26 similar in construction to the one previously described and configured to the shape of the block, is fitted over the block and the wires sprung into engagement with the slots 12 and/or 13. As above noted, a plurality of flyer wires may be made use of, where desired, by the simple expedient of using the pair of double slots 12, rather than the pair of single slots 13. For easy manufacturing and to avoid duplication of parts, the two series of slots 12 and 13 may be formed in a single device, either set being used at will by the operator.

The novel flyer cap and block assembly of the present invention is characterized by extremely low cost of manufacture, due to the fact that the wooden blocks may readily be formed by automatic machinery and the flyer caps may be stamped or pressed out from sheet metal of suitable thickness.

It will now be appreciated that there has been provided a plurality of flyer block constructions in which a unitary flyer cap of sheet metal or other like construction and of suitable size and configuration is adapted to be used and thus permit the use of replaceable flyer wires without requiring dismounting or removal of the flyer blocks from their respective spindles.

In accordance with the provisions of the patent statutes, I have described the principles of operation of my invention, together with the device which I now consider to represent a preferred embodiment thereof; but I desire to have it understood that the device shown is only illustrative of the basic concept of the present invention, and that the said invention may be carried out by other means.

I claim:

1. A flyer including an apertured body having an offset flange at the bottom, a head portion having an annular peripheral groove, a flyer wire disposed in the groove, and a separable cap fitted over said head.
2. A flyer including an apertured body having an offset flange at the bottom, a head having an annular peripheral groove, a flyer wire disposed in the groove, a separable cap fitted over said head, and means in the cap for tensioning the flyer wire.
3. A flyer including an apertured body having an offset flange at the bottom, a head having an annular peripheral groove, a flyer wire disposed in the groove and abutting thereagainst, a removable flyer cap fitted over said head, means in the cap for tension-

ing the flyer wires, said means including slots in the skirt of the cap.

4. A removable flyer cap including a skirted body portion and an apertured top portion, said skirt being provided with a plurality of wire engaging slots.

5. A removable flyer cap including a skirted body portion and an apertured top portion, said skirt being provided with a plurality of opposed wire engaging slots.

6. A removable flyer cap including a skirt and an apertured top, and reentrant slots in said skirt.

7. A removable flyer cap including a skirt and an apertured top, and reentrant slots in said skirt adapted to receive flyer wires.

8. A removable flyer cap including a skirt and an apertured top, and a plurality of reentrant slots in said skirt.

9. A flyer including an apertured body of fibrous material, an annular peripheral groove in said body, a flyer wire disposed in said groove, and a flyer cap on said body and in tensioning relation with said wire.

10. A flyer including an apertured body of fibrous material, an annular peripheral groove in said body, a flyer wire disposed in said groove, and a separable flyer cap on said body and in tensioning relation with said wire.

11. A flyer including an apertured body of fibrous material, an annular peripheral groove in said body, a flyer wire disposed in said groove, and a manually removable flyer cap on said body and in tensioning relation with said wire.

In testimony whereof I affix my signature.

MICHAEL J. McHALE.
